CAN OPENER AND SEALING CLOSURE

Miles O. Polson, Flagstaff, Ariz.

Application April 11, 1947, Serial No. 740,925

2 Claims. (Cl. 30—6.1)

1

This invention relates to a can opener, particularly of the type adapted to punch spaced openings in the end of a can of juice, milk, or other fluid product, and in particular, includes a device having two spaced prongs adapted to be forced into the end at opposite sides of a can wherein, after forming the openings, the prongs provide means for sealing the openings, and the device also includes a sealing gasket and means clamping the gasket against the end of the can.

The purpose of this invention is to provide a combination can opener, wherein elements thereof may be used to form fluid-removing openings in an end of a can, and then used as means for sealing the openings, and in which other elements thereof may be used as means for sealing the end of the can.

Numerous types of fluid products are provided in tin cans, and after opening the cans the products remain therein, only small amounts being used once in a while. In some products, such as canned milk, a film of milk remaining around an opening where it is exposed to the atmosphere is dehydrated to such an extent that it often closes the opening. In other cases where cans remain in the open, the contents are exposed to flies and other insects, and for some products it is desirable to completely seal the can protecting the product therein from the atmosphere. With these thoughts in mind, this invention contemplates a can-opening device by which spaced openings are formed in an end of a can and the openings and the end of the can are sealed by the device.

The object of this invention is, therefore, to provide an improved can opener that not only provides openings in the end of a can, but also seals the openings when not in use and furthermore provides a complete cover and closure for the end of the can.

Another object of the invention is to provide a can opener and sealer having operating instrumentalities associated therewith wherein the device may be clamped on the end of a can and also readily released therefrom.

A further object of the invention is to provide an improved can opener and sealing closure which is of a simple and economical construction.

With these and other objects in view, the invention embodies a disc with downwardly extending arcuate sides adapted to fit snugly around the sides of a can, a sealing gasket on the under side of the disc, prongs extending from the disc through the gasket, outwardly extending gripping

2

arms positioned to grip the outer surface of the can, and means actuating the gripping arms to locking and releasing positions.

Other features and advantages of the invention will appear from the following description, taken in connection with the drawings, wherein:

Figure 1 is a view showing a side elevation of an end of a tin can with the can opener and sealer positioned thereon.

10 Figure 2 is a plan view of the device as illustrated in Figure 1.

Figure 3 is a view showing a side elevation of the device, looking from a point at right angles from that of Figure 1, and having a part broken away showing the construction of the parts.

Figure 4 is a plan view looking upward toward the under side of the actuating disc with the gripping jaws and other parts omitted, taken on line 4—4 of Figure 3.

20 Figure 5 is a view showing a side elevation similar to that shown in Figure 3, illustrating a modification, wherein spring clips are used at the sides instead of the arcuate, downwardly extending flanges.

25 Figure 6 is a cross-section through the can opener illustrated in Figure 5 showing the spring clips at the sides.

Referring now to the drawings, wherein like reference characters indicate corresponding parts, the new and novel can opener of this invention includes a disc 10, a smaller disc 11 pivotally mounted on and positioned above the disc 10, and outwardly extending gripping jaws 12 and 13 pivotally mounted on the disc 10 by pins 14 and 15.

35 The disc 10 is substantially the same diameter as the periphery of a can upon which the device may be used, and, in the design illustrated in Figures 1 and 2, the disc is provided with downwardly extending arcuate flanges 16 and 17 which fit snugly against the outer surface of the can, as shown in Figure 1. Extending downwardly from the under surface of the disc 10 are two oppositely positioned prongs 18 and 19

40 which are adapted to penetrate an end 20 of a can 21, as illustrated in Figure 6. In positioning the can opener on the end of a can, the flanges 16 and 17 are placed over the can and by pressing downward with the palm of the hand, or by striking the end of the device lightly with the fist, the prongs 18 and 19 are forced through the end of the can providing openings therein. A gasket or sealing disc 22 that may be made of rubber or other resilient material is nested 45 against the under surface of the disc 10, as

shown in Figure 3, wherein with the can opener positioned on the end of a can, the gasket provides sealing means completely closing the can.

The upper disc 11 is pivotally mounted on a centrally disposed pin 23 extending upward from the disc 10, and this disc is provided with outwardly extending upwardly flared arms 24 and 25 by which it may be rotated about the pin 23 to lock the jaws 12 and 13 against the can, or release the jaws from the can. The disc 11 is provided with a cam 26 positioned in line with the projections 24 and 25 and located between the inner ends of the jaws 12 and 13. With the jaws 12 and 13 pivotally mounted on the pins 14 and 15, the cam 26 is between the inner ends of the jaws, and as the disc 11 is rotated in a clockwise direction, as illustrated in Figure 2, the cam will be moved to the dotted line position 27, thereby spreading the inner ends of the jaws 12 and 13 and forcing the outer ends 28 and 29 against the surface of the can. With the ends 28 and 29 positioned below a bead 30 at the end of the can, as illustrated in Figure 1, the jaws will draw the disc 10 with the gasket 22 against the end of the can, thereby sealing the entire end of the can. To release the device from the can, the disc 11 is rotated in the opposite or counterclockwise direction, wherein projections 31 and 32 on the under surface of the disc engage inner edges of the jaws 12 and 13 and force the jaws outward away from the surface of the can.

In the design shown in Figures 5 and 6, the can opener and sealer is formed with a disc 33 similar to the disc 10, and the edges of the disc are provided with downwardly extending gripping prongs or spring fingers 34 and 35, which resiliently position the device on the end of a can. In this design the disc 11 with its associated parts and gripping jaws 12 and 13 are similar to corresponding parts in Figures 1 and 2, and, therefore, the same reference numerals are used for both. With the parts arranged in this manner, the can opener and closure of this invention may be provided in different sizes corresponding with cans upon which it may be used, and when it is desired to open a can to remove juice or other fluids therefrom, the device may be pressed against the end of the can, as hereinbefore described, wherein the prongs 18 and 19 will form openings in the can. The device may then be removed so that the entire content may be poured from the can, or only a small amount of the product may be removed, and then the device may be replaced with the prongs 18 and 19 filling the openings providing sealing means therefor. When it is desired to further seal the end of the can, the disc 11 may be rotated in a clockwise direction, wherein the cam 26 will force the inner ends of the jaws 12 and 13 outward and thereby force the outer ends inward in gripping relation with the can, and with the jaws 12 and 13 positioned to engage the under surface of the bead 30, inward movement thereof will draw the gasket or sealing disc 22 downward against the end of the can, thereby sealing the entire end thereof.

It will be understood that modifications may be made in the design and arrangement of the

parts without departing from the spirit of the invention.

What is claimed is:

1. A perforating and sealing closure for tin cans comprising a substantially flat disc for arrangement adjacent to one end of the can, a resilient sealing gasket secured to the bottom of the disc and engaging the end of the can between such end and disc, perforating means secured to the disc for puncturing the end of the can when the sealing gasket is pressed into engagement with the end, a plate rotatably mounted upon the disc and arranged in spaced superposed relation with respect to the disc, a pair of gripping arms pivotally connected with the disc and disposed between the top of the disc and rotatable plate, said arms including outer depending extensions which project radially beyond the side of the can and are adapted to engage such side, and a cam secured to the bottom of the rotatable plate and arranged between the arms for engaging the arms to swing the depending extensions into engagement with the side of the can when the rotatable plate is turned.
2. A perforating and sealing closure for a tin can comprising a substantially flat rigid disc arranged adjacent to the end of the can to be perforated, a resilient sealing gasket secured to the bottom of the disc and engaging the end of the can for sealing it, spaced prongs secured to the disc and projecting inwardly of the gasket for perforating the end of the can when the closure is applied to the can, a plate rotatably mounted upon the disc and disposed in spaced superposed relation with respect to the disc, a pair of substantially flat elongated gripping arms disposed between the top of the disc and rotatable plate and pivotally connected with the disc between their inner and outer ends, the arms being freely swingable over the disc and including outer substantially U-shaped depending extensions adapted to engage the side of the can below the end thereof, and an elongated cam secured to the rotatable plate for movement therewith and arranged between the plate and disc and between the inner ends of the arms, the cam engaging the inner ends of the arms for spreading them apart and swinging the depending U-shaped extensions into engagement with the side of the can when the rotatable plate is turned.
